UNITED STATES PATENT OFFICE

2,676,505

SPREADER WRENCH

Austin G. Goodnight, Laton, Calif.

Application March 28, 1950, Serial No. 152,411

2 Claims. (Cl. 81—48)

1

The present invention relates generally to tools and more particularly to a spreader wrench.

The wrench of the present invention is adapted for use in connection with the attachment and/or removal of battery connectors from electrical storage batteries. For convenience, the device of the present invention is shown and described as employed with a battery connector of the type illustrated and described in my co-pending application for "Clamping Devices," Serial No. 10 675,448, filed June 8, 1946 and now Patent No. 2,548,782. In that application is shown a battery connector having a pair of jaw members adapted to engage a battery post with resilient means for urging the jaw members toward each other in clamping relation. In the disclosure, no mechanical aid is provided to facilitate the spreading of the jaw members in attaching the connector to a battery post or for removing the connector from a battery post. It has been found advantageous to provide a pair of wrench openings or bores in the jaw members and to provide a wrench of the type comprising the subject matter of the instant application to engage the wrench openings in the jaws as a connecting and disconnecting expedient.

Therefore, it is an object of the present invention to provide an improved wrench adapted to facilitate positive positioning and spacing of relatively yieldable members.

Another object is to provide a wrench adapted to facilitate the spreading of relatively movable resiliently clamping jaw members of battery connectors to condition the battery connector for convenient attachment and removal from a battery post.

Another object is to provide a wrench, by the use of which, a separable battery connector may be easily and quickly attached to a battery post or removed therefrom.

Another object is to provide a wrench of the type described which is convenient and simple to operate in even relatively inaccessible positions.

Another object is to provide a wrench for spreading battery connectors which is operable in various attitudes relative to the battery connector.

Another object is to provide a battery connector wrench that is economical to manufacture, durable in construction, easy to assemble, and dependable in its operation.

Still further objects and advantages will become apparent in the subsequent description in the specification.

In the drawings:

Fig. 1 is a plan view of a wrench embodying the principles of the present invention.

Fig. 2 is a side elevation of the wrench.

Fig. 3 is an end view of the wrench as viewed from the right end of Fig. 2.

2

Fig. 4 is a perspective view of the wrench shown in the preceding figures.

Fig. 5 is a plan view of a second form of the present invention.

Fig. 6 is a somewhat enlarged fragmentary side elevation of a work piece engaging end of the wrench illustrated in Fig. 5.

Fig. 7 is a perspective view of a battery connector of one type with which the wrench of the present invention finds utility, fragmentarily showing bore engaging pins supported thereabove preparatory to operable engagement therewith.

Referring in greater detail to the drawings:

One of the forms of the wrench of the present invention identified in Figs. 1 to 4, inclusively, by the reference numeral 10, consists primarily of a pair of elongated levers 11 of any desired cross section each having an ear 12 formed integrally therewith and extending normally thereto adjacent corresponding ends thereof. Each lever has a relatively short extension at one side of its ear and a relatively longer extension at the opposite side thereof. A pintle 13 extends through the ears 12 so that the levers 11 are pivotally connected for relative movement in a common plane. The longer extending portions of each of the levers 11 constitute handles 14. A torsion spring 15, having outwardly turned or bent terminal ends 16, is located under initial torsion between the handles 14 with the ends 16 of the spring each extending into an opening 17 drilled into the inwardly disposed faces of each of the handles a short distance from the pivotal interconnection of the levers. The torsion spring is located under initial torsion between the handles 14 and urges the handles apart.

The shorter portions of the levers 11 comprise arms 20 each of which has an inwardly disposed stop rod 21 conveniently mounted in openings 22 individual to the levers in juxtaposition. The stop pins on the arms 20 are in substantial longitudinal alignment for endward abutting when the handles 14 are urged pivotally outwardly by the spring 15. The length of the stop pins 21 are such that they limit pivotal movement inwardly of the arms 20 to substantially parallel relation.

An operating pin 23 is conveniently formed integrally with each of the arms 20 and extends endwardly from its respective arm. It is to be understood that the operating pins 23 may be formed separately and securely attached endwardly of the arms 20 so that they are movable therewith without departing from the spirit or scope of the present invention. Laterally extended operative pins 24 are individually secured, as by a press fit, into a base 25 formed in each of the arms 20 and extend substantially perpendicularly to the common plane of the arms adjacent to the terminal ends thereof. The pairs of operating pins 23 and 24 are selectively en-

gageable with relatively movable members and by manipulation of the handles 14 the members may be positively relatively positioned.

Second form

A second form of the present invention is shown in Figs. 5 and 6 of the drawings substantially similar to the first form in the provision of pivoted levers 11, each having a handle portion 14 and an arm portion 20, with the hands urged outwardly by means of a torsion spring 15. Like numbers identify portions of the first and second forms of the invention that are similar.

In the second form of the invention, however, a substitute structure for the stop rods 21 is employed and the arms 20 terminate in bifurcated end portions 27, clearly shown in Fig. 6. Arm extensions 28 having endwardly disposed transversely arranged tongues 29 individually fitted to the end portions 27 are articulately connected to the end portions by headed pintles 30 extended therethrough. The arm extensions 28 are thus mounted for pivotal movement in the plane of the levers 11. The pintles 30 are extended in parallel relation perpendicularly from the levers 11 in alignment with the articulately connected arms 20 and extensions 28 to provide operating pins 31 corresponding to the operating pins 24. Operating pins 33 similar to pins 23 are endwardly extended from the arm extensions in parallel relation.

The second form of the present invention differs from the first form in the provisions of means for maintaining the endwardly extended operating pins 33 in parallel relation during manipulation of the levers 11. Such means consists of a guide rod 35 secured to one of the arm extensions 28 and rigidly extended perpendicular therefrom toward the opposite arm extension. A guide sleeve 36 is rigidly secured to, and extends perpendicular from, said opposite arm extension and telescopically receives the guide rod. As evident in Figs. 5 and 6, the guide rod 35 and sleeve 36 are preferably aligned with the pivotal interconnection of the arms 20 and their respective arm extensions 28. To achieve this, the guide rod and the sleeve are mounted on the bifurcated portions of their respective arm extensions so as to avoid interference with the pivotal association of the extensions and their respective arms. When the arms 20 are moved relatively by operation of the handles 14, the arm extensions and their respective operating pins 33 are constrained to parallel positions by slidably telescopic coaction of the guide rod 35 and guide sleeve 36. As will subsequently become apparent, the maintenance of the operating pins 33 in parallel relation precludes binding thereof in engageable bores or other openings in work pieces having relatively movable portions.

The wrench of the present invention is adapted to be used in connection with relatively movable members which are resiliently urged together but separable from each other. An example of a structure with which the wrench is used is illustrated in Fig. 7 of the drawing showing a battery connector 37 adapted to be connected to a battery post, not shown, of an electrical storage battery. The battery clamp is provided with a head 41 and a relatively movable cap 42. A cylindrical or frusto-conical connector opening 43 is formed transversely through both the head and the cap symmetrically of their parting line. The head and the cap provide a pair of

jaws 44 at opposite sides of the opening which are adapted to engage opposite sides of a battery post when in properly installed position. A pair of bores or pockets 45 are formed downwardly into the head 41 and the cap 42 closely adjacent to the opening 43. The bores are adapted to receive either the operating pins 23, 24, 31 or 33 of the wrenches of the present invention for effecting the separation of the jaws. The head 41 and cap 42 are maintained in relative alignment by means of a pair of headed studs 46 passed through the cap 42 and either threaded or engaged with a press fit into the head 41. A counterbore 47 is formed in the cap 42 concentrically of the headed stud 46 and a compression spring 48 is located in circumscribing relation around each of the headed studs 36 and under initial compression between the head of each stud and the bottom of the counterbore 37 yieldably to maintain the head 41 and the cap 42 in engagement and their jaw portions 44 in constricting relation.

Operation

25 The operation and utility of the present invention is believed to be apparent from the foregoing description and is briefly summarized at this point. The wrenches are adapted to be used forcibly to separate yieldably separable members such as the jaw portions of the battery clamp exemplified in Fig. 7 of the drawing. To separate the jaws of the battery clamp the operating pins 23, 24, 31 or 33 are inserted into the bores or pockets 45. The selection of the endwardly extended operating pins 23 or 33 or laterally extended pins 24 or 31 to insert in the bores 45 is determined by handling convenience and available working space. After the pins are inserted in the bores 45 the handles 14 of the wrench are squeezed toward each other pivotally separating the arms 20, pins, and portions of the battery connector in which the bores are formed. This separates the jaws 44 of the battery clamp so that they may be located over a battery clamp 40 for connection therewith or removed from a battery clamp for detachment therefrom. In attaching a battery clamp to the post of a battery, after the jaws 44 are located in circumscribing relation around the battery post the handles of the wrench are released permitting the jaws to move toward each other under the urging of the springs 48 firmly engaging the jaws with the post of the battery.

45 It will be apparent that in employing the pins 23 in the bores 45, pivotal movement of the levers pivots said pins therewith. Unless the pins have a relatively sloppy fit in the bores, this results in binding and limiting of pivotal movement of the levers. Of course, the laterally extended pins 24 and 31 are always in parallelism and thus do not experience such binding. Further, the second form of the invention provides a structure positively maintaining the endwardly extended pins 33 in parallel relation similarly overcoming any tendency to bind.

50 The wrenches of the present invention are not limited to use in mounting and removing battery connectors of the type described but may be suitably employed in positively spacing relatively movable objects having pin receiving bores or pockets formed therein. Not only do the wrenches serve positively to space such objects but through engagement with pockets and/or bores formed therein hold the objects and permit their positioning as desired.

The devices of the present invention facilitate the positive positioning and spacing of relatively yieldable members having bores formed therein and provide for the expeditious attachment and detachment of battery connectors of the type described. The wrenches are economical to manufacture, durable in construction, easy to assemble and dependable in operation.

Although I have herein shown and described my invention in what I have conceived to be the most practical and preferred embodiment, it is recognized that departures may be made therefrom within the scope of my invention, which is not to be limited to the details disclosed herein, but is to be accorded the full scope of the claims so as to embrace any and all equivalent devices and structures.

Having described my invention, what I claim as new and desire to secure by Letters Patent is:

1. A spreader wrench comprising a pair of levers each having a handle end portion and an endwardly bifurcated opposite end portion, a pintle pivotally interconnecting the levers intermediate their opposite end portions, an extension individual to each lever having a lip received in the bifurcated end of its respective lever, a pair of pins in parallel relation to the pintle extended through the bifurcated ends of the levers and the lips therebetween pivotally connecting the extensions to their respective levers, a rod extended from one extension toward the opposite extension substantially radially of the pivot pin of its respective extension, and a sleeve extended from said opposite extension substantially radially of its pivot pin slidably receiving the rod for relative

telescopic movement, and work piece engaging means mounted on the extensions.

2. A spreader wrench comprising a pair of levers each having a handle end portion and an endwardly bifurcated opposite end portion, a pintle pivotally interconnecting the levers intermediate their opposite end portions, an extension individual to each lever having a lip received in the bifurcated end of its respective lever, a pair of pins in parallel relation to the pintle extended through the bifurcated ends of the levers and the lips therebetween pivotally connecting the extensions to their respective levers, a rod extended from one extension toward the opposite extension substantially radially of the pivot pin of its respective extension, and a sleeve extended from said opposite extension substantially radially of its pivot pin slidably receiving the rod for relative telescopic movement.
